(57) **CLAIM**

The ornamental design for a makeup mirror, as shown and described.

DESCRIPTION

FIG. 1 is a top, front, left-side perspective view of a makeup mirror showing my new design;

FIG. 2 is a bottom, rear, right-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a partially enlarged view thereof, taken from FIG. 3;

FIG. 10 is a partially enlarged view thereof, taken from FIG. 3;

FIG. 11 is a partially enlarged view thereof, taken from FIG. 8; and,

FIG. 12 is a partially enlarged view thereof, taken from FIG. 8.

The broken lines shown in the drawings depict portions of the makeup mirror that form no part of the claimed design. The evenly-spaced dashed lines shown in the drawings depict portions of the makeup mirror that form no part of the claimed design. The dot-dash broken lines encircling portions of the makeup mirror in FIGS. 3 and 8 and illustrated in enlarged views in FIGS. 9-12 form no part of the claimed design.

1 Claim, 11 Drawing Sheets
